UNITED STATES PATENT OFFICE

2,252,564

SPLIT-FOOT KNITTING MACHINE

Isaac H. C. Green, Central Falls, and Eugène St. Pierre, Pawtucket, R. I., assignors to Hemp-hill Company, Central Falls, R. I., a corporation of Massachusetts

Application October 18, 1939, Serial No. 300,058

9 Claims. (Cl. 66—41)

This case concerns an invention applicable to split-foot knitting machines and wherein elastic tops may be knitted in conjunction with the well-known split-foot. The invention is to be described with respect to the accompanying figures of drawing wherein like numerals are applied to corresponding parts and wherein:

Fig. 1 is an elevation showing parts of a split-foot knitting machine as seen from the front and wherein the invention has been applied;

Fig. 2 is an elevation showing certain parts of the machine as seen from the auxiliary side;

Fig. 3 is a similar view taken at the right hand or main side;

Fig. 4 is a plan view of the carrier ring, yarn feeding levers and binders as employed;

Fig. 5 is a sectional view through the cylinder and showing certain cams and part of their controlling means, which cams function upon needle jacks;

Fig. 6 is a detail showing an eyelet closing cam, a needle dividing cam and part of the controlling means for the latter;

Fig. 7 is a detail of a so-called front jack cam and part of the controlling means for the same;

Fig. 8 is a plan of the sinker cap and sinker cams, parts being broken away to show the cams, the auxiliary, center sinker cam being shown in a withdrawn or inactive position;

Fig. 9 is a similar view showing the center sinker cam in active position;

Figs. 10 through 15 are views showing certain cams on a main cam drum for controlling the various functions of the machine as they apply to knitting of an elastic top and cooperating parts of a stocking;

Figs. 16 through 18 show three types of needle jacks employed;

Fig. 19 is a diagrammatic view showing needle and jack butt pathways at that point in the knitting cycle whereat the so-called eyelet closing cam is functioning;

Fig. 20 is a similar diagrammatic view but showing needle and jack butt pathways during knitting an elastic top; and

Fig. 21 is a conventional view of a split-foot article of hosiery wherein an elastic top has been knitted such as might be knitted by the machine herein described.

The elastic top which is to be applied to a circular, seamless, split-foot stocking and which the machine herein described is adapted to produce is to be like or similar to that described in St. Pierre Patent #2,131,720. In addition to the structure specifically described in that patent,

this machine will produce a tuck stitch top such as described in co-pending application Serial #295,095, filed September 14, 1939. In the knitting of such a simulated rib, elastic garter top on a split foot machine, certain problems have arisen and have been solved in a manner which will be evident as the following disclosure progresses.

Referring to the figures of drawings, especially Figs. 1, 2, 3 and 4, a typical split-foot knitting machine has been illustrated having a frame 1, circular base 2, needle cylinder 3, sinker head 4 and sinker cam cap 5. There are two feeding points and adjacent each of these feeding points a set of stitch cams such as is normally employed in this type of machine. A plurality of yarn guides generally designated by numeral 6 are pivoted at 7 at the main side of the machine, said yarn guides being controlled by the usual levers 8 which connect to and are controlled through a series of wires extending downwardly in bracket 9 and being moved by certain suitable cams on a main cam drum such as disclosed in United States Patent #933,443. While the said levers 6 function at the main side within appropriate guiding means in an extension of the carrier ring 10, at the opposite side (auxiliary side) two yarn feeding levers have been provided, the lever 11 serving to feed a non-elastic yarn 12, that yarn being knitted in the instep of the stocking. A second and similar feeding lever 13 has threaded therethrough an elastic yarn 14 which is to be incorporated in the stocking top to serve as a garter and to draw the fabric into a rib appearance. These levers 11 and 13 are pivoted at 15 and normally are urged into a raised or inactive position by springs 16, 16' engaging the projecting pins 17, 17'.

These levers have outwardly and downwardly extending projections to which are attached hardened contact pieces 18 and 19. A bell crank lever pivoted at 20 and having a vertical arm 21 and a horizontal arm 22 serves by an inwardly projecting end of the arm 21 engageable under the contact piece 18, to move lever 11 against the tension of spring 16 to a feeding position. A second bell crank lever pivoted opposite the point 20 has a vertical arm 23 and a horizontally extending arm 24 similar to those indicated at 21 and 22. An inwardly projecting end of arm 23 engages beneath contact piece 19 to control the elastic yarn feeding lever 13 in a similar fashion.

Referring to Figs. 1, 19 and 20 cam plate 25

carries the usual main cam block having thereon a front stitch cam 26, back stitch cam 27, center cam 28 and guard cam 29. The usual narrowing picks function in a manner well-known. The entire cam block may be withdrawn at desired times as on conventional Banner machines and separate means is provided for withdrawing the front stitch cam at desired points in the knitting.

At the auxiliary side an auxiliary cam block is movable to and from an active position, the general construction of this cam block and cams thereon being described in United States Patents Nos. 2,083,027, 2,161,067 and 2,142,693. The usual widening picks are mounted at that point and their operation is too well understood to be necessary of further description at this time. At the auxiliary side of the machine the stitch cams 30, 31 and center guard cam 33 function in a more or less conventional manner. The stitch cams are movable only as a unit with the cam block itself, while center guard cam 33 is independently movable by mechanism hereinafter to be described. Superposed wing cam 34 is fixed at the inner end of a stem 35, Fig. 1, and is a conventional part of such machines.

At the front of the machine a block generally indicated at 36 carries the so-called instep cams which function on long needle butts to raise them prior to knitting in the heel or toe or to return them to active level upon completion of either of those elements. Reference is made to United States Patent #2,083,027 for a full description of these cams, their function and mechanism for actuating them at proper intervals.

A main cam shaft 37 has at its left hand end a drum 38 to which are attached certain cams hereinafter to be described in greater detail with respect to Figs. 10 through 15 wherein each row of cams which effects knitting herein described has been shown in detail. This drum rotates once during the knitting of a complete stocking or article and thus each row of cams controls its particular element and all functions attendant thereupon, throughout the knitting of one complete article after which the cycle is repeated.

Referring to Fig. 4, a yarn binder assembly of the usual type employed in split-foot machines is mounted on the carrier ring 10 and includes a bracket 39, plate 40 and a binder element 41 for yarns at the main side. A second binder generally indicated by numeral 42 serves to bind the non-elastic yarn 12 at the auxiliary side. The elastic yarn is not taken within a binder as this particular machine has been constructed. It is practical to float the elastic yarn at such times as it is not being incorporated in the fabric and while a slightly greater amount of elastic is used that way, the amount is more or less negligible. It is contemplated to use a separate binder for the elastic or to use a binder so constructed as to serve both the elastic and inelastic yarns at that side.

The usual needles and sinkers are employed and according to one preferred form of the invention, jacks are to be used beneath every other needle, these jacks being of long butt and short butt types corresponding to the long and short butt groups of needles. These jacks have been shown in Figs. 16-18, the jacks being generally indicated by numeral 43 and having for general purposes, short butts 44 and long butts 45. At one side of the group it is customary to employ about three needles specially controlled by jacks for closing the eyelet upon certain changes in the knitting, this function and manner of so doing

being described in Patent #2,083,027. Since jacks are placed beneath every other needle and are to function for other purposes, those jacks have been specially constructed as shown in Fig. 18 to have an extra short butt 46 and a long butt 47, the extra short butt being at the same level as the butts 44 and 45 while the butt 47 is at a different and higher level. According to the set-up, two of the jacks are to have butts 47 and in addition the extra short butts 46. Those jacks would be numbers 1 and 3 of the eyelet closing group while the jack intermediate them (Number 2 jack) would have only the upper butt 47. The manner in which these jacks are caused to function in the various parts of the knitting which they control will be described in greater detail at a later point in the disclosure.

Several cams function upon these jacks, one of which is termed a front jack cam and is indicated by numeral 48, Figs. 1, 5, 7 and 20. That jack cam is affixed to one arm 49 of a bent lever pivoted at 50 on a bracket 51 attached to the base 2. This lever is bent as illustrated in Fig. 7 so that the cam 48 inclines at approximately 45 degrees and will, when projected to the position of Fig. 5, raise all jacks by contact with the butts 44, 45 or 46. The height of this cam is such as to raise jacks and attendant needles to that point to which they would normally be raised if the front stitch cam were in position, that is, to a latch clearing level. The said lever has a second arm 52 projecting outwardly and engaged by a more or less vertically extending arm 53 of a second lever pivoted at 54. This second lever has another short, projecting arm 55, to which is attached a depending link or bar 56 which, as shown in Fig. 1, extends down through a guiding element 57 to be engaged by a cam 58 on the drum 38, Figs. 1 and 13.

An angular stop 59 is fixed to the arm 52 and has in its downwardly depending part a stop screw 60 engageable with the side of bracket 51 whereby an adjustment may be set so that the cam 48 will move inwardly close to the cylinder and for proper contact of jack butts. A spring 61, Figs. 5 and 7, tends to maintain the cam in active position except when, under the influence of cam 58 on the drum 38, bar 56 is moved upwardly swinging lever arm 53 to the left, Figs. 5 and 7, thereby withdrawing the cam against the tension of said spring 61.

An eyelet closing cam having two cam elements 62 and 63 is fixed to one end of lever 64 capable of swinging on a pivot 65 at the top of a bracket 66, Figs. 2, 3, 5 and 6. This lever is guided by the shoulder screws 67 which passes through a slot 68. At the other end lever 64 has attached thereto a link 69 which projects over to the opposite side of the machine frame and is under the control of mechanism heretofore described and claimed in United States Patents Nos. 2,083,027, 2,161,067 including a lever 70, link 71, Fig. 3, and other mechanism not necessary to describe at this point.

This eyelet closing cam functions at such times as it would normally function in knitting any sort of split-foot hosiery, but the cam itself has been constructed in a particular fashion for the purpose of controlling three jacks having butts 47, Fig. 18, and for allowing other jack butts to pass along at a lowermost level unaffected by the cam at that time. For that purpose the cam is made in two parts including an outer cam 62 which extends approximately to the base of the machine as illustrated in Figs. 5, 6 and 19,

while the inner cam 63 is cut off at its lower part leaving a sufficient space for jack butts to pass beneath as will be described more thoroughly with respect to the operation and Fig. 19.

A third cam known as the needle dividing cam completes the group of cams which function upon needle jacks. This dividing cam 72, Figs. 5, 6 and 20 is fixed at the inner end of a stem 13 which is guided within an appropriate slot in bracket 66. The stem has a projection 74 at its outer end engageable by an arm 75 of a lever pivoted at 76 on an extension 77 which is in turn attached at the side of bracket 66. The second arm 78 of the lever connects by a link 79 to an angularly bent lever 80 pivoted at the side of the machine at a bracket generally indicated by numeral 81, Fig. 5. This lever 80 has a depending bar 82 attached adjacent its forward end which bar extends downwardly to engage a cam 83 on the drum 38, Figs. 1 and 12. Cam 72 is normally maintained in innermost position by tension spring 84, Figs. 5 and 6. At such times as it is to be withdrawn, cam 83 will raise the bar 82 and by means of the mechanism just described will draw the cam outwardly to an inactive position. When in its innermost position all jacks would be raised so that prior to approaching the elastic yarn feed, corresponding needles will be raised high enough to take said elastic yarn in their hooks.

It will be noted that cam 83 has a step 85 at one end and at the other end a corresponding step 86. The purpose of these will be described more fully with respect to operation of the machine.

Yarn feeding levers 11 and 13 and those cooperating levers 22 and 24 have been described, it being understood that the said levers 11 and 13 are maintained in raised or inactive position except at such times as moved to feeding position by pulling downwardly upon the appropriate lever arm 22 or 24. Two links 87 and 88 connect to the arms 22 and 24, respectively, and are in turn attached to levers 89 and 90, Figs. 1 and 2. These levers 89 and 90 are pivoted within a bracket 91 and at their forward ends are attached to depending links or bars 92 and 93. The bar 92 is controlled by a cam 94 while the bar 93 is affected at appropriate times by one or the other of cams 95 or 96, Figs. 1, 10 and 11. Cam 94 controls the lever 13 so as to feed the elastic yarn at appropriate intervals while the cams 95 and 96 affect lever 11 causing it to feed its yarn in the knitting of said parts of a split-foot stocking, namely, in the instep opposite the high-splice and sole of the foot.

Referring to Figs. 1 and 14, part of a mechanism for controlling the auxiliary center guard cam is shown. A series of cams 97, 98 and 99 function upon a bar 100 connected to a lever 101 to move the said center cam through other connecting means including the link 102, lever arm 103 and a spindle 104 passing through the support at the main side of the machine located beneath plate 25. This spindle 104 passes through to the back of the machine and by another lever and a link connected to the horizontally disposed lever 105, Fig. 1, controls the movement of said center cam 33, Fig. 19. This center cam functions during the knitting of a stocking top, in the high-splice and in the foot. A more thorough description of operation as controlled by cams on drum 38 will be included in a later paragraph.

At times the front stitch cam 26 at the main

side is to be withdrawn. That stitch cam has a sliding stem which connects by means of link 106 to lever 107 pivoted at 108, then by lever 109 to link 110 which passes down through the guide 57 to contact a cam 111, Figs. 1 and 15. As this cam 111 raises the link or bar 110, the said cam 26 will be withdrawn; at other times a spring (not shown) will maintain it in needle butt engaging position.

Referring to Figs. 8 and 9, the sinker cam cap generally indicated by numeral 5 has been shown in greater detail and the sinker cams 112, 113 and 114 at the main side are shown imparting a stitch wave 115 to sinker butts at that side. At the other side there are the usual split-foot side sinker cams 116 and 117 and the auxiliary center sinker cam 118 which is movable as in this type of split-foot machine. As shown in Fig. 8, at which time no yarn would be knitted at the auxiliary side, that sinker cam 118 would be projected inwardly by mechanism disclosed in patents numbered 2,083,027 and 2,142,693 so that the sinker butts are unaffected and sinker nibs hold the fabric down on the needles. In Fig. 9 that cam 118 has been moved outwardly to impart to sinkers a stitch wave as their butts pass in the pathway 119. This cam 118 assumes the position shown in Fig. 9 when the split-foot yarn is feeding and also when the elastic yarn feeds at that side.

Operation

In Figs. 19 and 20 pathways of needle and jack butts have been shown during certain phases in the knitting cycle. In Fig. 20 knitting is shown as it takes place during the knitting of a top with elastic incorporated therein. At the main side of the machine front stitch cam 26 has been withdrawn since the bar 110 has risen upon cam 111, Fig. 15. The remaining cams are in active position at that side and a yarn fed through the yarn guiding finger 6 will feed to the hooks of all needles as they pass through the cams at that side of the machine. Cam 48 will be in active position at the start of knitting in the top if a so-called tuck top is to be knitted. Cam 48 is moved inwardly when lever 57 drops from cam 58, Fig. 13. Jack butts will move from a level at 120 to a level above cam 48 indicated by numeral 121. Since jacks are provided beneath every other needle, those needles will move from a level at 122 as they pass along raise cam 123 to an elevation at 124 which is at a corresponding height, that is, the same height to which needles would be raised if front stitch cam 26 were in position. Those needles which do not have jacks beneath them pass along at the level 122 to take yarn and those needles are merely accumulating loops since their latches have not been cleared. Stitches are drawn as needles pass down stitch cam 27.

At the auxiliary side stitch cams 30 and 31 are in active position while center guard cam 33 has been moved inwardly against the cylinder as lever 100 moves up on cam 97. Dividing cam 72 is moved inwardly against the cylinder as bar 82, Fig. 12, drops from cam 83. That cam first moves inwardly on short butts as the bar drops to the level 85 and thereafter drops all the way downwardly so that both long and short butt jacks will be affected. Raise cam 125 allows needle butts to approach at a level 126 and at that level, all needles would pass beneath cam 31 so that none would take any yarn at the auxiliary side. However, the cam 72, in raising jacks,

raises alternate needles to a level at 127 whereupon those needles which take the elastic yarn fed by yarn feeding lever 13 and will draw that yarn into knitted stitches as needles pass beneath cams 33 and 30. The level 127 is a latch clearing level so that the elastic stitches thus drawn are actually drawn through the last knitted plain yarn loops drawn at the main side. Plain yarn loops on intermediate needles are not affected at this side of the machine.

The cam 48 is also affected during the knitting of so-called breaking thread courses knitted prior to starting the elastic top. At that time the breaking thread is knitted on every other needle so that as cam 26 is withdrawn, only those needles having jacks beneath them will take the breaking thread and knit it.

After knitting the tuck top, it being preferable to knit two series of tuck courses, the stitch cam 26 will be projected in and cam 48 may be withdrawn. Cam 26 will be projected inwardly between the series of tuck courses. It would do no harm to allow cam 48 to remain in for the duration of knitting the entire top, although that is not necessary. At any points throughout or at the end of the top, cam 26 may again be withdrawn, 48 being projected inwardly and other series of tuck stitches knitted, the method and fabric thus being produced being fully described in co-pending application Serial #295,095.

At certain phases of knitting in split-work it is desirable to control a group of three needles to take an extra yarn to produce an overlap thereby preventing an eyelet in the finished fabric. That occurs at certain yarn changes and at strokes in a clockwise direction of knitting. At that time all cams are in needle butt engaging position at both feeding points and to effect this eyelet closing the so-called eyelet closing cam 62 is projected to a position for engaging three butts 47 on jacks 43. As before described a cam 63 has been attached to the inner surface of cam 62 so that in effect, cam 63 acts upon these butts 47 in conjunction with cam 62, the other butts 44, 45 and 46 passing beneath this cam 63 so that no jacks other than the three mentioned will be raised at this time.

Needle butts move along over raise cam 125, rise up cam 27, and take yarn and knit beneath cams 29 and 26. Only those needles which knit at the main side in split-work are thus affected. Jacks are passing along so that butts 44, 45 and 46 are moving in pathway 128 while butts 47 move in a slightly higher pathway 129. After passing beneath stitch cam 26, the needles that knitted at the main side move up raise cam 123 to reach the level 122, then pass beneath cams 30 and 31. The opposite group of needles would, of course, knit at the auxiliary side, but that is not being shown since it is not necessary to illustrate all the various pathways for the points herein involved. Since it is desirable for three of those needles, butts of which pass beneath cam 30, to take yarn at the auxiliary side, the three jacks having butts 47 move up cams 62 and 63 so that jack butts 47 reach an elevation at 130 and needle butts an elevation at 131. Hooks of those three needles will take yarn from the yarn guide 11 as shown. The remaining jacks having butts 44 and 45 are not affected by cams 62 or 63 merely passing along at the level 128, the butts passing beneath cam 63 in the clearance provided. The cam 63 is moved to such a position that the extra short butts 46 move up to pathway 128 but do not interfere with cam 63 in so doing.

Referring to Figs. 10 and 11 the split-foot yarn fed by lever 11 is controlled in the high-splice by cam 95 and in the foot of the stocking by cam 96. The elastic yarn fed by lever 13 is under the control of cam 94, Fig. 11. Three cams on drum 38 affect movements of the auxiliary center guard cam, those cams being shown in Fig. 14. Cam 97 functions while elastic is knitted in the top, cam 98 in the high splice and cam 99 in the foot.

The auxiliary sinker center cam 118, Figs. 8 and 9, is automatically controlled as levers 11 and 13 feeding the split-foot and elastic yarns are moved to and from feeding position. The control for that cam has been described in prior patents, one or more of which have been mentioned above with respect to this particular cam.

In Fig. 21 an anklet has been illustrated having short leg portion 132, a split foot having instep part 133, sole 134 and high splice 135. The heel 136 and toe 137 are such as are usually knitted on this type of hosiery. The top 138 is knitted as in St. Pierre Patent #2,131,720 and serves as a garter as well as being knitted to resemble true rib fabric.

The invention has been described in a description of a preferred embodiment of the same, but many changes may occur to those skilled in the art but which would fall within the scope of the invention as originally conceived. The invention is defined in the following claims:

We claim:

1. In a knitting machine the combination of means for knitting split fabric including two feeding stations, means thereat for feeding non-elastic yarns, means for feeding an elastic yarn at one of said feeding stations in combination with needle dividing means for presenting spaced needles to take said elastic yarn and to knit it in combination with non-elastic yarn knitted at the other feeding station.

2. In a knitting machine the combination of means for knitting split fabric including means for knitting non-elastic yarns at two separate feeding stations, means for feeding and knitting an elastic yarn at one of said stations and at the other, means for knitting tuck stitches of a non-elastic yarn capable of being controlled selectively to knit such stitches throughout desired courses in which elastic yarn is incorporated.

3. In a knitting machine the combination of means for knitting split fabric including two separate feeding stations, means for feeding non-elastic yarns at said stations, and at one of them, an elastic yarn, means for dividing needles to take said elastic yarn and to incorporate it in the fabric at spaced wales and at the other of said feeding stations, means for controlling needles to knit tuck stitches of a non-elastic yarn at selected courses wherein elastic yarn is incorporated.

4. In a knitting machine the combination of means for knitting split fabric and means for incorporating an elastic yarn in plain fabric knitted by feeding a non-elastic yarn at one feeding station and an elastic yarn at another feeding station, said means for incorporating elastic yarn including means for dividing needles to receive the elastic yarn including a dividing cam and jacks, all of said jacks which affect needles that take elastic yarn having a butt adjacent their lower end engageable with the dividing cam, a cam in advance of the main yarn feeding station for engagement with said jack butts to raise needles to a latch clearing position for

tucking and means for selectively moving said cam to and from butt engaging position.

5. In a knitting machine the combination of means for knitting split fabric including two feeding stations and knitting cams at each of said stations, means for feeding non-elastic yarns at both stations and an elastic yarn at one of said stations, needle selecting means for raising spaced needles to take elastic yarn including jacks and a needle dividing jack cam, said jacks having butts adjacent their lower ends, means functioning upon said jacks in split-foot knitting for eyelet closing, certain of said jacks having an additional butt at a different level from the needle dividing butts, the construction being such that said needle dividing butts are not affected by the eyelet closing cam and eyelet closing butts are not affected by said dividing cam.

6. In a knitting machine of the type described the combination of an eyelet closing cam, jacks serving to select needles for eyelet closing and also to select them for taking and knitting an elastic yarn having butts for each purpose, the construction of said eyelet closing cam being such that it will function only upon butts on jacks adapted to raise needles for eyelet closing and will permit butts which control selection for taking elastic yarn to pass unaffected.

7. In a knitting machine, the combination of a needle dividing cam and an eyelet closing cam, jacks beneath needles adapted to raise certain needles for eyelet closing purposes and at other

times, to raise needles for knitting an elastic yarn, said jacks having two butts, one slightly above the other and the top butt longer than the bottom, means for moving the needle dividing cam inwardly to engage the bottom butts for raising needles to take elastic yarn, means for moving said dividing cam to inactive position and other means for moving the eyelet closing cam to a position for engaging the long butts at the upper position but for avoiding the lower or short butts.

8. In a split-foot knitting machine, an auxiliary yarn feed having thereat means for feeding an elastic yarn and separate means for feeding a non-elastic yarn, means for moving either of said yarns to feeding position selectively, means for causing adjacent needles to knit the non-elastic yarn and other means for causing only spaced needles to take and knit the elastic yarn when it is fed.

9. In combination in a split-foot knitting machine, an eyelet closing cam, jacks having butts of one length at one level, said jacks having another butt of a different and shorter length at a lower level, certain other jacks having at said lower level long butts equivalent in length to the butts first mentioned, said cam having a butt raising portion but being further cut away at its lower edge for allowing long butts at the lowermost level to pass without interference.
